(57) **CLAIM**

An ornamental design for a bed bug trap, as shown and described.

DESCRIPTION

FIG. 1 is an upper perspective view of a first embodiment of a bed bug trap in accordance with the present invention; FIG. 2 is a lower perspective view of the bed bug trap shown in FIG. 1;

FIG. 3 is a front view of the bed bug trap shown in FIG. 1, which is the same as a rear view;

FIG. 4 is a left side view of the bed bug trap shown in FIG. 1, which is the same as a right side view;

FIG. 5 is a top view of the bed bug trap shown in FIG. 1;

FIG. 6 is a bottom view of the bed bug trap shown in FIG. 1; FIG. 7 is an upper perspective view of a second embodiment of a bed bug trap in accordance with the present invention;

FIG. 8 is a lower perspective view of the bed bug trap shown in FIG. 7;

FIG. 9 is a front view of the bed bug trap shown in FIG. 7, which is the same as the rear view;

FIG. 10 is a left side view of the bed bug trap shown in FIG. 7, which is the same as a right side view;

FIG. 11 is a top view of the bed bug trap shown in FIG. 7; and, FIG. 12 is a bottom view of the bed bug trap shown in FIG. 7.
